UNITED STATES PATENT OFFICE.

VITALIS HIMMER, OF NEW YORK, N. Y., ASSIGNOR TO THE TIME TELEGRAPH COMPANY, OF SAME PLACE.

CIRCUIT-CONTROLLER FOR ELECTRIC CLOCKS.

SPECIFICATION forming part of Letters Patent No. 274,323, dated March 20, 1883.

Application filed September 16, 1882. (No model.)

To all whom it may concern:

Be it known that I, VITALIS HIMMER, a citizen of the United States, and a resident of the city of New York, in the county and State of New York, have invented certain new and useful Improvements in Circuit-Controllers for Electric Clocks, of which the following is a specification.

My invention has reference to that class of electric time-indicators in which a central regulating-clock governs or regulates one or more secondary clocks included in one and the same electric circuit, the connections of which circuit are established and broken at regularly-recurring intervals by the movements of the central clock.

Heretofore it has been usual, in systems of this kind, to include certain of the moving parts of the regulating-clock in the electric circuit. It has been found in practice that this arrangement interferes with the correct action of the clock mechanism, in consequence of the variable expansion of the metals under the influence of the heat generated by the passage of the currents. Moreover, the electrical connections soon become uncertain and imperfect, and constant care and attention are required to keep the whole in working order.

The object of my invention is to provide a simple and efficient circuit controller or breaker having no electrical connection with the moving parts of the regulating-clock, but which is nevertheless adapted to be actuated by the pendulum at each oscillation, the connection therewith being such as not to interfere in any way with its normal action.

To this end my invention comprises a light pivoted lever, which is preferably counterbalanced and placed in a position parallel with the pendulum and at a short distance therefrom. The upper end of the lever is connected with the pendulum by means of a horizontal bar, preferably of insulating material. An adjustable clamp is also placed on the pendulum-rod near its point of suspension. The horizontal bar is not connected directly with said clamp, but is pivoted to an intermediate rod, which is provided with means for accurately adjusting the perpendicular position of the lever. The lever also carries below its point of

suspension a contact-pin, normally insulated from but capable of moving to and fro between two other contact pins or plates, thus forming an electrical connection therewith alternately as the pendulum swings back and forth. By means of this device an electric circuit is opened and closed at each beat of the pendulum, in which are included any required number of secondary clocks of suitable construction. The contact pins or plates between which the pin upon the lever moves are mounted upon slender adjustable springs, by which means perfect electrical contact is assured, while the mechanical resistance offered by the device is rendered so small as to produce no appreciable effect upon the oscillations of the pendulum.

In the accompanying drawings, which illustrate my invention, Figure 1 is a front elevation of the circuit-breaker, showing in diagram its electrical connections with the secondary clock, and Fig. 2 is a side elevation of the same.

Referring to the drawings, A represents the pendulum-rod of a suitable central clock or regulator, which may be actuated by a spring, cord, and weight, electrically or otherwise. The pendulum-rod A is suspended by its upper extremity from a bracket, B, secured to the back-board b or to the frame-work of the clock.

In the drawings I have not deemed it necessary to show any means for imparting motion to the pendulum-rod A, for the reason that the invention relates exclusively to the circuit-breaker and the means of actuating it by the movements of a pendulum, without reference to the particular manner in which the pendulum itself is actuated.

Secured to the back-board b is a standard, C, from which extends an arm, c, for supporting the circuit-breaking device, the position of the latter being preferably a little distance beyond the normal swing of the pendulum-rod A. The frame-work D of the circuit-breaking device is secured to the arm c in its proper position with reference to the pendulum-rod A by means of a suitable clamping-screw, c', which extends through a threaded hole into an aperture, c², corresponding in form with the arm c, along which the circuit-breaker is con-

structed to slide. The position of the circuit-breaker with reference to the pendulum-rod A may be adjusted by moving the same along the arm e to the proper point and fixing it in 5 that position by tightening the clamping-screw c'.

The circuit-breaker itself consists of two metallic wires or springs, e e', supported upon arms E and E', which in turn are mounted upon 10 the frame D. A pin, f, carried upon the short arm of the lever F, projects between the pins or wires e and e', which form one electrode of a battery, o, being electrically connected therewith through the frame D, standard C, 15 binding-screw c', and wire l. The lever F is mounted upon the axis g, turning in suitable bearings, g' and g'', in the upper portion, d', of the frame-work D, which is insulated from the lower portion, d, by means of a block, D', of 20 hard rubber or other suitable material, to which both are secured. The lever F terminates at its upper extremity in a long light rod, G'', and is preferably counterbalanced by means of the extension G', which is so proportioned that the 25 upper arm, G'', will be very nearly or quite balanced in whatever position it may at any time be placed.

A flexible metallic strip or ribbon, H, preferably of silver rolled very thin, forms an electrical connection between the lever F and frame 30 d', one end of it being secured to the latter by a screw, h, while the other end is secured to the lever, near to or opposite the trunnion g', by means of the screw h'.

35 A binding-post, I, is provided for making an electrical connection from a battery, o, with the frame-work of the apparatus by means of the wire 2.

It will be understood that when the lever F is caused to oscillate the pin f will come alternately in contact with the wires e and e', thereby closing the circuit of the battery o.

The means for communicating the required motion to the lever F from the pendulum A 45 consists of a flexible bar, k, the lower end of which is secured to the pendulum-rod A by means of an adjustable clamp, K, constructed to embrace the pendulum or to be firmly affixed thereto in any required vertical position.

To the upper end of the flexible arm k is pivoted a link, L, preferably of non-conducting material—such as hard rubber or ivory—the opposite end of which is pivoted to the upper extremity of the lever F.

55 For the purpose of adjusting the position of the lever F with reference to the pendulum A, so that the lever shall stand in a position midway between the wires e and e' when the pendulum is at rest, I provide an adjusting-screw, 60 k', which extends through a corresponding threaded hole formed in the flexible arm k near its extremity. The adjusting-screw k' serves to bend the spring-arm outward from the pendulum-rod by pressing the same, as shown in 65 Fig. 1.

It will be evident from the foregoing explanation that each vibration of the pendulum-rod

A will be communicated to the lever F by means of the spring-arm and connecting-link L, thereby causing the contact-pin f to be 70 brought alternately into electrical connection with the contact-wires e and e', thus closing a circuit from the battery o, through the wire 2, binding-post I, flexible ribbon H, to the lever F; thence through the pin f and contact-wire e 75 or e' to the lower portion, d, of the frame-work D, bracket C, binding-post c', and wire 1, through the clock M, to the other pole of the battery o.

For the purpose of securing accurate adjustment of the various parts of the device, I provide, in addition to the means already described for adjusting the position of the lever F with reference to the clock-pendulum, the following means for adjusting the positions of 85 the contact-wires e and e' with reference to the contact-pin f. The supports E and E', for carrying the wires e and e', are themselves supported upon a bar, D'', secured to the lug d' 90 upon the lower portion, d, of the frame D. A screw, i, binds the lower extremities of the arms E and E' upon opposite sides of the upright D'' by passing through an elongated hole or slot, i', formed therein. By loosening the 95 screw i the vertical positions of the arms may be varied, thereby changing the positions of the pins e and e' with reference to the point of contact with the pin f whenever such change is desired on account of the wearing away of the wires e and e' by the friction caused by repeated contacts.

For the purpose of adjusting the normal distance between the wires e and e' and their distance from the contact-pin f, I provide two adjusting-screws, m and m', which turn in corresponding threads formed in the arms E and E', respectively, and by pressing against the upright D'' may be caused to spring the arms E and E' outwardly to any required distance. By means of this adjustment I am enabled to 110 secure a uniform interval of contact between the pin f and each of the wires or pins e and e', and at the same time to place the former in such a position that a contact will be made therewith only when the lever F is near the 115 limit of its vibration.

In addition to these adjustments, I prefer to mount the wires e and e' upon the thin flexible arms or springs l and l', which are of any suitable conducting material which will readily 120 yield to a slight pressure exerted upon the wires. The springs l and l' are secured to the arms E and E', respectively, by means of suitable binding-screws, l'' and l''', which are constructed to turn in corresponding threads 125 formed in the arms E and E', respectively. The springs may be revolved about the centers formed by the screws l'' and l''', and secured in the required positions by tightening the same. This construction provides not only for the 130 delicate contact between the pins and contact-wires, but also permits the wires e and e' to be adjusted in a horizontal position with reference to the pin f whenever such adjustment is de-

sired to bring into use a different point upon the length of the pin *f*. The pin *f* may also be made adjustable by extending it through an aperture, *n*, formed in the lever *F*, and securing it in its required position by a set-screw, *n'*, projecting into the aperture *n* at right angles thereto.

It will be observed that the contact-pin *f* is caused by the vibration of the pendulum *A* to vibrate through a small arc, and to come into contact with the wires *e* and *e'* at the respective extremities of that arc. The contact which is made with these wires will, owing to the flexibility of the springs *l* and *l'*, be a frictional contact, caused by the sliding of the pin *f* upward upon the wires *e* and *e'* during the remaining portion of its vibration after coming in contact therewith. In this manner the contact-surfaces will be kept bright and a good electrical connection will be at all times insured.

To prevent the lever *F* from being swung through an arc of too great an amplitude, I provide suitable limiting-stops, *p* and *p'*, projecting from the frame-work *d'* beyond the normal limit of vibration of the lever.

Instead of employing flexible arms for supporting the pins *e* and *e'*, small rigid weighted levers may be employed.

In some instances it may be found desirable to employ only one of the pins, *e* or *e'*, so that the circuit will be closed when the pendulum *A* swings to one side only, thus causing the electric clocks included in the circuit 1.2 to beat 35 seconds when the pendulum of the regulating-clock beats half-seconds.

I claim as my invention—

1. The combination, substantially as herein-before set forth, with a clock mechanism and a vibrating pendulum, of an electric circuit-breaker mechanically operated by said pendulum, but insulated therefrom and from said mechanism.

2. The combination, substantially as herein-before set forth, with the pendulum of a regulating-clock, of a circuit-controlling device consisting of a pivoted lever, a contact-pin mounted upon said lever and electrically connected with one pole of a battery or electric generator, contacts placed at opposite sides of said contact-pin and in electric connection with the opposite pole of said battery or electric

generator, and a link connecting said lever with said pendulum, whereby a vibratory movement is communicated from the pendulum to the lever, and the contact-pin is brought into contact with said contacts alternately at each vibration.

3. The combination, substantially as herein-before set forth, of a clock-pendulum, a circuit-closing lever, mechanism, substantially such as described, for imparting a vibratory motion to said lever, electrical contacts at opposite sides of said lever, and an adjustable contact-pin carried upon said lever and alternately placed by the vibrations of the lever in electrical connection with said contacts, respectively.

4. The combination, substantially as herein-before set forth, of a clock-pendulum, a circuit-closing lever, a spring-arm attached at one end to said pendulum, a link uniting the opposite extremity of said spring-arm to said lever, and a set-screw for adjusting the position of the upper extremity of said spring-arm to and from the pendulum-rod.

5. The combination, substantially as herein-before set forth, of a pivoted circuit-closing lever, a contact-pin carried upon the short arm of said lever, electrical contacts at each side of said contact-pin, flexible springs for supporting said contacts, and means, substantially such as described, for adjusting the longitudinal positions of said contacts.

6. The combination, substantially as herein-before set forth, of a circuit-breaking lever, a contact-pin mounted thereon, a contact at each side of said contact-pin, and flexible arms for supporting the respective contacts, and means, substantially such as described, for adjusting the lateral positions of said flexible arms.

7. The combination, substantially as herein-before set forth, of a circuit-closing lever, a contact-pin mounted thereon, a contact at each side of said pin, flexible or yielding supports for said contacts, and means, substantially such as described, for adjusting the vertical and lateral positions of said supports and contacts.

In testimony whereof I have hereunto subscribed my name this 9th day of September, A. D. 1882.

VITALIS HIMMER.
